RADIATOR CAP

James A. White and David B. Mecorney, Lockport,
N. Y., assignors to General Motors Corporation,
Detroit, Mich., a corporation of Delaware

Application September 3, 1936, Serial No. 99,200

8 Claims. (Cl. 220—24)

This invention relates to fluid pressure responsive means to lock a closure member against removal when a pressure differential exists between the interior and exterior of an engine cooling system or the like.

There are certain well known advantages to be obtained if the circulating liquid in an engine cooling system is maintained under a few pounds pressure and a number of automobile manufacturers have adopted the closed system which includes a blow-off valve acting automatically to relieve excess pressure through the overflow vent pipe. In a system of this kind it is here proposed to prevent removal of the filler cap at times when internal pressures are present, in order to avoid the possibility of injury by scalding, damage to the car finish, loss of cooling liquid and other undesirable resultants of vomition of the system contents through the filler opening.

In a preferred embodiment of the invention as designed for convenience, compactness, economy and simplicity, there is provided as a part of the detachable cap assembly a movable plunger fitting the filler opening for outward projection under internal system pressure into position to engage a fixed abutment which holds the cap assembly against removal. Also incorporated in the cap assembly is a spring seated valve which opens a port in the plunger to communicate the system with the overflow vent pipe leading from the filler spout for the relief of pressure in excess of a predetermined value.

For a better understanding of the structure involved reference may be made to the accompanying drawing wherein Figure 1 is a side elevation of the cooling radiator and its connections with the front of the engine; Figure 2 is a vertical sectional view of the filler assembly; Figure 3 is a similar view with the parts in position to prevent removal of the filler cap; Figures 4 and 5 are, respectively, sectional views taken on line 4—4 of Figure 2 and line 5—5 of Figure 3, and Figure 6 illustrates the application of the invention to an alternate type of cap retainer.

In the drawing the radiator fan 1 and the pump assembly 2 are mounted on a common shaft driven by a belt 3 from the engine crank-shaft, for drawing air through the radiator core 4 and circulating water or other cooling medium through the system. The system includes the radiator core 4 and the jacketed engine block 5 having an outlet connection 6 with the inlet header 7 of the radiator and being supplied with water from the pump 2 which is joined by the connection 8 with the outlet header 9 of the radiator.

For filling the system, the top tank is provided with a rearward extension 10 which has

in the top wall, a filling opening defined by a dependent annular flange 11 and an upstanding spout 12. The spout is closed by a removable cap 13 which may comprise a sheet metal stamping and the connection between the cap and spout may be of any conventional type, as for example, the familiar bayonet slot connection by which the cap is applied or removed by partial rotation thereof. Accordingly, the cap has riveted or otherwise secured internally thereof, a disc 14 which clamps in place the sealing gasket 15 and carries at diametrically opposite points dependent legs 16 terminating in outwardly extending feet 17, and the spout in turn is provided with a camming edge at the bottom of a dependent sleeve 18 for engagement with the feet or lugs 17. The sleeve 18 is formed as a part of the inturned flange 19 on the spout and at given points both the flange and the sleeve are cut away as at 20 in Figure 4 to allow the passage of the lug 17 when the cap is moved axially of the spout with the lugs alined with the slots.

In the present case the disc 14 also carries a pair of spaced arms 21 having axially elongated slots 22 through which extend a transverse rod or shaft 23, the ends of which are riveted or peened over the ears 24 on a stamped cup 25, constituting a plunger or piston. By reason of the pin and slot connection 23—22, the plunger is assembled as a unit with the cap and is permitted an axial movement relative to the cap within limits defined by the slot. This plunger is so constructed as to have a sliding fit within the dependent annular flange 11 for closing the filling opening when the cap is in its retained position on the filler spout 12. Also mounted on the pin 23 is the curled eye 26 on one end of a coil spring 27, which seats at the other end within a pocket on the top of a disc valve 28, seated by the spring over an opening in the plunger 25 and guided for outward movement against the resistance of the spring, by a series of spaced guide fingers 29 projecting into the opening. The spring is so selected as to allow the valve to open outwardly under internal pressure of predetermined value for communicating the interior of the system with the filler spout, from which leads the usual overflow pipe 30 extending outwardly and downwardly beside the radiator core for discharge at the bottom of the radiator assembly.

Inside the spout there is secured to the wall thereof a semi-circular strip 31 terminating in a pair of oppositely positioned inturned abutment lugs 32 and these lugs are adapted for engagement by bifurcated ears 33 extending outwardly from the upper edge of the plunger 25. The cooperating interengaging parts 32 and 33 are so positioned with relation to each other and the

retained position of the filler cap 13 that the presence of internal pressure within the system will lift the plunger 25 for keying the parts 32 and 33 to lock the cap against rotation. Thus 5 after the cap is once positioned on the filler spout it can be removed only when the plunger is in the retracted position and, therefore, the likelihood of damage caused by gushing of hot water and steam through the filler spout by internal pressure is eliminated.

The fit of the plunger 25 within its guide flange 11 is such as to allow free relative movement, and while sealing means may be added to reduce leakage, it is preferred merely to provide a close running fit. This may permit a slight fluid escape without material detriment to satisfactory system 15 operation and will relieve low pressure when the spring pressed valve 28 is closed. The clearance may be quite large if the system is operated open 20 to outside pressure without disturbing the locking action of the plunger. In other words, the operation of an open system under certain conditions is such that pressure builds up at a rate higher than the capacity of the overflow pipe to relieve it, and 25 the automatic locking of the closure cap is a safety factor to avoid serious consequences.

With a close fit between the piston plunger 25 and flange 11 the cooling system operates, after an initial warm-up period, under a slight internal 30 pressure which raises the boiling point of the liquid for increased cooling efficiency and conservation of the liquid supply. Excess pressure is prevented through the automatic action of the relief valve 28. Subatmospheric pressure within 35 the system is avoided by the provision of a small bleed hole or vent port 34 in the skirt of the plunger 25, so positioned that the port 34 is closed by the cylindrical wall or flange 11 when the plunger is raised, but is uncovered below the 40 flange whenever the plunger is dropped in the absence of internal pressure.

Figure 6 illustrates the application of the pressure control device to a cap and filler spout of the type having external attachments. In this 45 case the filler spout 12' has an outturned flange 19' from which extends downwardly the cam skirt 18' for engagement by a pair of diametrically opposite turned lugs 17' on the closure cap 13'. Rotatably mounted on the cap are a gasket 35, of rubber or the like, and a pressure ring 36 of spring metal for peripheral sealing engagement with the top flange 19' of the spout. At their inner margins, the rings 35 and 36 have a loose fit within 50 a shouldered portion of the mounting element 14' riveted or otherwise secured to the cap. The lower ends of the dependent arms 21' below the slots for the transverse shaft 23' of the plunger 25', in this instance, are offset inwardly as at 37 to afford a seat for a coil spring 38 which bears 55 against the bottom of the plunger. The optional addition of the spring 38 may be made to insure a more positive downward or return action of the plunger. The construction and operation otherwise is as before described.

65 We claim:

1. An engine cooling system having a filling opening, an upstanding spout surrounding said opening, an overflow vent pipe leading from said spout beyond said filling opening, a closure cap 70 rotatably engageable with said spout for movement to and from its closed position, a plunger fitted to said opening to restrict system communication with said vent pipe, an outwardly opening valve associated with said plunger to communicate the system with the vent pipe for the relief 75

of abnormal internal pressure, means joining the plunger and cap for unisonal rotation while permitting relative axial movement of the plunger in said opening and means carried by the spout for engagement with the plunger in its pressure projected position to lock the closure cap against rotation. 5

2. An engine cooling system having a filling opening, an upstanding spout surrounding said opening, an overflow vent pipe leading from said spout beyond said filling opening, a closure cap 10 rotatably engageable with said spout for movement to and from its closed position, a pair of spaced arms on the cap depending into the spout and having transversely aligned axially elongated 15 slots therein, a transverse shaft projecting between said arms and into said slots for axially guided movement, a plunger carried by said shaft and fitted to said opening, an outwardly opening valve adapted to close a port in the plunger, a 20 spring interposed between said shaft and valve, and interlocking formations on the plunger and spout adapted for engagement when the plunger is projected outwardly by internal system pressure. 25

3. A radiator closure, including a rotatable cap 30 adapted for removable engagement with a filler spout, a pressure actuated plunger, means joining the cap and the plunger for rotation in unison and for relative axial movement and an abutment on said plunger adapted to be projected into interlocking relation with a stop on a filler spout. 35

4. In an engine cooling system having a filler spout and a removable closure cap, a plunger 35 movably supported on the cap and adapted for relative movement in response to internal system pressure, and means on the spout to be engaged by said plunger to preclude removal of the cap. 40

5. In an engine cooling system having a vented 45 filler spout and a removable closure cap, a pressure actuated piston carried by the cap and slidably fitted to a cooperating portion of the spout, cap locking means engageable by the piston, and a vent port in the piston wall which is closed by 50 said spout portion when the piston is in engagement with said locking means.

6. In an engine cooling system having a vented 55 filler spout and a removable closure cap, a pressure actuated piston carried by the cap and slidably fitted to a cooperating portion of the spout, cap locking means engageable by the piston, a vent port in the piston wall which is closed by 60 said spout portion when the piston is in engagement with said locking means, and a pressure actuated valve in said piston to relieve excess system pressure through the vented spout. 65

7. In an engine cooling system, a vented filler spout, a closure therefor, interengaging closure locking members on the closure and spout, respectively, including a pressure actuated piston, piston guide means, and a vent in the wall of the piston adapted to be closed by said guide means when 70 said locking members are engaged.

8. In an engine cooling system, a vented filler 75 spout, a closure therefor, interengaging closure locking members on the closure and spout, respectively, including a pressure actuated piston, means associated with the piston for relieving excess internal system pressure and other means 80 associated with the piston for relieving subatmospheric internal system pressure. 70
